UNITED STATES PATENT OFFICE.

WILLIAM E. WHITE, OF CHICAGO, ILLINOIS.

INSERT HOLDER.

Application filed August 18, 1921. Serial No. 493,473.

To all whom it may concern:

Be it known that I, WILLIAM E. WHITE, a citizen of the United States, and resident of Chicago, in the county of Cook and State 5 of Illinois, have invented certain new and useful Improvements in an Insert Holder, of which the following is a specification.

My invention relates to inserts and particularly to a novel device intended for use 10 in securing inserts to forms prior to the pouring of concrete around such inserts. The device here disclosed is an improvement upon that shown in my co-pending application, Serial No. 445,315, filed Feb. 16, 1921, 15 and is a continuation in part of my application Serial No. 464,877.

One of the objects of my invention is to provide a device of the character described, which may be easily applied without the 20 use of separate nails and which possesses unusual facility in the matter of separation and removal of the fastening element after the form has been stripped.

It is customary in order to secure inserts 25 in proper position to provide notched ears at the sides thereof and to hold the same in place by means of nails driven into the form. These serve the desired purpose of securing the insert in its position but after the form 30 is stripped, the nails project beyond the face of the concrete and must be cut off in a subsequent operation. This is an expensive and tedious operation and it is avoided in the construction here disclosed.

35 In my device I provide a staple which is adapted to interfit with the insert and to be assembled and shipped as a part thereof, the pointed ends of the staple projecting beyond the bottom face of the insert. The 40 arrangement is such that the prongs of the staple may be driven into a wooden form by a blow applied to the top of the insert. After the form is stripped the staple may be disengaged by a simple operation and in 45 many cases is adapted for reuse if desired. However, the cost thereof is so slight that reuse is not essential.

The invention will be more readily understood by reference to the accompanying 50 drawing, in which,

Fig. 1 is a longitudinal sectional view through an insert and fastener constructed in accordance with my invention;

55 Fig. 2 is a transverse sectional view on the line 2—2 of Fig. 1;

Fig. 3 is a bottom plan view, and,

Fig. 4 is a sectional view on the line 4—4 of Figs. 1 and 2.

The insert illustrated herein is the same as that shown in my copending application 60 heretofore referred to. It consists of a box 10, having an anchor provided with a flanged head 11, formed as a part thereof. The bottom wall of the box is constructed to provide a key-hole slot, the notched portion 12, of which is shaped to permit the insertion of the head of a bolt while the flanges or lips 13, which surround the narrow portion 14 of the slot serve as supports for said head. The flanges 15, which surround the enlarged portion of the opening 65 serve to support a U-shaped keeper 16, mounted for vertical movement between the walls of the box. In operative position the keeper rests upon the flanges 15 and 70 serves as a support for the bolt-head.

As a means for securing the insert in position and for retaining the keeper in an inoperative position prior to the necessity for use, I provide a staple which consists of an 80 arched portion 17, and legs or prongs 18, the ends of which are sharpened.

It will be noted that the flanges 15, which surround the enlarged portion of the slot, are notched at their junction with the flanges 85 13, the notches extending inwardly to a point close to the plane of the side walls. These notches receive the legs 18 of the staple which, when the staple is installed, 90 are straight as shown in full lines in Fig. 2. There is, however, a space 19 between the staple legs and the side wall and when a driving force is applied to the portion 11 of the device, in order to cause the points 95 of the staple to enter a wooden form, the force is directed against the arched intermediate portion of the staple and if the wood into which the staple is to be driven is at all hard the staple will be flared or distorted into the dotted-line position of Fig. 2. The insert is thus firmly held against 100 accidental displacement prior to the pouring of the concrete. When, however, the form has been stripped the staple is easily removed by slightly compressing the legs toward each other and withdrawing the same 105 downwardly.

A staple constructed as shown is easily manufactured, requiring no special dies in the forming machine and the castings will, 110 under ordinary practice, contain a recess or indentation 20 at the axis of the anchor.

This recess, which engages the apex of the staple together with the notches which receive the legs, serves to firmly hold the staple in position for the driving action.

5 Obviously the construction is capable of much modification and I do not wish to be limited except as indicated in the appended claims.

I claim:

10 1. In an insert, the combination of a housing adapted to be embedded in concrete and having an internal recess for the accommodation of a bolt head, and a U-shaped fastener adapted to project into the recess and to interlock with the housing, said fastener having pointed ends adapting it to be driven into a form.

20 2. In a device of the class described, the combination of a housing having a keyhole slot in its bottom wall, a movable keeper adapted to co-operate with the enlarged portion of said slot, and a staple a portion of which is within and interlocks with said housing and serves to retain said keeper in a fixed position, the ends of said staple projecting outside of the housing and serving as a means for securing the housing to a form.

30 3. In a device of the class described, the combination of a housing having a keyhole slot in its bottom wall, a movable keeper adapted to co-operate with the enlarged portion of said slot, and a staple a portion of which is within and interlocks with said housing and serves to retain said keeper in an inoperative position, the pointed ends of said staple projecting outside of the housing and being adapted to be driven into a form, the staple being removable after the 40 form is stripped, thereby permitting the keeper to assume an operative position.

4. In an insert, the combination of a

housing adapted to be embedded in concrete and having an internal recess for the accommodation of a bolt head, a notched flange 45 adjacent to said recess, and a staple co-operating with the notch in said flange and fitting within the recess in said head, said staple serving as temporary fastening means for said housing.

5. In an insert, the combination of a housing adapted to be embedded in concrete and having an internal recess for the accommodation of a bolt head, a notched flange adjacent to said recess, and a staple having 55 a V-shaped head fitting within the recess, a leg of the staple co-operating with said notch.

6. In an insert, the combination of a housing having an opening for the reception of a bolt head, a flange at each side of said opening, the flanges at each side being notched at a point midway of the length of the housing, and a staple having a V-shaped head fitted within the housing, the legs of 65 the staple occupying notches in said flanges.

7. In an insert, the combination of a housing having an opening for the reception of a bolt head, a flange at each side of said opening, the flanges at each side being 70 notched, said notches being of a depth slightly less than the width of the flange, and a staple fitted within the housing and having a head adapted to contact with the top wall of the housing only at a point midway between the legs, the legs of the staple occupying the notches in said flanges, the arrangement being such that as a driving force is applied to the staple through the 75 housing the top of the staple is flared.

Signed at Chicago, Illinois, this 3rd day of August, 1921.

WILLIAM E. WHITE.
